UNITED STATES PATENT OFFICE.

EDWARD RYAN, OF CHICAGO, ILLINOIS, ASSIGNOR TO LOCOMOTIVE STOKER COMPANY,
OF PITTSBURGH, PENNSYLVANIA, A CORPORATION OF PENNSYLVANIA.

LOCOMOTIVE-TENDER.

1,270,214.

Specification of Letters Patent. Patented June 18, 1918.

Application filed October 11, 1916. Serial No. 125,113.

To all whom it may concern:

Be it known that I, EDWARD RYAN, a citizen of the United States, and resident of Chicago, county of Cook, and State of Illinois, have invented certain new and useful Improvements in Locomotive-Tenders, of which the following is a specification, and which are illustrated in the accompanying drawings, forming a part thereof.

10 The invention relates to a locomotive tender provided with a fuel bin and with power mechanism for advancing the fuel therein.

15 The objects of the invention are to provide for a simple and comparatively inexpensive arrangement of the fuel advancing mechanism and tender walls, to protect the power mechanism of the fuel-advancing means against injury in loading and without seriously trespassing upon the capacity 20 of the water tank of the tender, and to generally increase the efficiency of the device.

An embodiment of the invention is hereinafter described, and is illustrated in the 25 accompanying drawings in which—

Figure 1 is a detail plan view of the tender, some of the parts being broken away;

Fig. 2 is a detail central vertical section 30 of the tender;

Fig. 3 is a sectional detail on the line 3—3 of Fig. 2;

Fig. 4 is a detail transverse sectional view 35 of the tender in perspective;

Fig. 5 is a detail sectional view on the line 5—5 of Fig. 2;

Fig. 6 is a detail central section of the 40 motor-controlling valve on the line 6—6 of Fig. 1.

Fig. 7 is a sectional view on the line 7—7 of Fig. 6; and

Fig. 8 is a longitudinal sectional view of the forward end of the valve mechanism.

The tender 10 is of common type, being provided at its forward end with a fuel bin and at its rearward end with a water tank, the latter extending forwardly along each side and below the fuel bin, as shown at 11, 12.

50 The fuel bin is provided with the usual flat floor 13, and at its rearward end with a slope sheet, the latter, however, in this instance having novel features.

The side walls 14, 15, of the fuel bin rise 55 vertically from the floor 13 for a short dis-

tance and then incline outwardly, as represented at 16, 17, to the outer walls of the tender. At its rearward end the floor 13 is curved upwardly, as shown at 13^a, for a short distance, this portion constituting the lower end of the slope sheet. The major portion of the slope sheet, designated by the numeral 18, is offset upwardly, terminating a short distance above the floor 13. The space between the two sections of 60 the slope sheet 13^a and 18 is closed, except at the central portion, by plates 19, 20.

A plate 21, shown as a continuation of the section 13^a of the slope sheet, extends 65 upwardly from the middle portion of the latter parallel with and back of the portion 18 of the slope sheet to the top or deck plate 22 of the tank. Wall plates, as 23, extend upwardly from the plates 19, 20, uniting the slope sheet 18 and plate 21, thereby forming 70 a chamber, open at its lower end for the accommodation of the pitman connecting the motor with a pushing element. Preferably the portion of the slope sheet 75 18 which covers this chamber is a separate 80 piece secured by rivets or other suitable means for convenience in assembling.

A pusher head 24 reciprocates over the rear portion of the floor 13 and its extension 13^a, its ends fitting under guide flanges 25, 85 26, secured to the vertical walls 14, 15, of the bin. This head may be provided with upwardly projecting oscillatable leaves 27, which, upon the backward movement of the pusher head, fold downwardly in order 90 that they may more easily slide under the fuel.

The pusher head is connected to the cross-head 28 of a motor, which reciprocates in the chamber referred to below the slope 95 sheet, by means of a pitman 29.

A reciprocating motor, the cylinder of which is designated 30, is located above the deck 22 and back of the slope sheet 18, and may be conveniently supported by 100 means of brackets 31, 32, secured to vertical plates 33, 34, joining the slope sheet 18 and deck. The axis of this motor is parallel with the slope sheet, and on the median line of the central chamber therebelow, its piston rod 35 being attached to the cross-head 28. Steam for actuating the motor is supplied through a pipe 36 from the locomotive, which is connected with a service pipe 37 leading from the forward end of the 105 110

fuel bin to a valve casing 38, mounted upon the deck 22, and from which lead the distributing pipes 39, 40, to the opposite ends of the motor cylinder.

It being desirable that a single stroke motor be employed, and that the pusher head remain at rest after each forward stroke, a suitable valve is provided for securing this result. For this purpose there is shown a cylindrical valve 41, having an annular cavity in its periphery, and reciprocating within the casing 28, and playing over ports 42, 43, which communicate, respectively, with the distributing pipes 39, 40,—exhaust ports 44, so located as to be always between the two annular faces of the valve, communicating with an exhaust passage 45 which preferably discharges into the water tank of the tender. The stem 46 of this valve extends through the service pipe 37, and a stuffing box 47 in its forward end, and is controlled by means of a suitable handle 48. The inner end of the valve stem is tubular, as shown at 49, and opens through the valve 41, being ported, as shown at 50, to permit the entry of steam. In the normal position of the valve steam is delivered to the upper end of the motor cylinder 30, the lower end thereof being open to the exhaust. A drain passage 51 is provided to permit the discharge of the water of condensation to the exhaust pipe from the cylinder back of the piston, when the latter is in its forward position. By this arrangement live steam is in the motor cylinder at all times and freezing is thereby avoided and the accumulation of water in the cylinder prevented.

The valve 41 is so proportioned that while it is substantially balanced, and hence easily operated, there is a slight preponderance of pressure at one end resulting in its automatic return to normal position after each manual movement.

By the construction shown and described the fuel will fall by gravity from the lower end of the slope sheet proper upon the floor of the bin. When the supply of fuel upon the front portion of the floor of the bin has been exhausted, the operator shifts the valve to cause the retraction of the pusher head and the latter slides under the mass of fuel, this movement being comparatively easy because the main weight of the mass is supported by the slope sheet. The valve is again shifted, either manually or by steam pressure, to deliver steam to the upper end of the cylinder, thus advancing the pusher head and with it an adequate supply of fuel for immediate use. Any fuel which may be carried into the chamber within which the pitman 29 is housed, is ejected by the cross-head 28. The motor and its parts are well protected from being damaged by the fuel when dumped into the tender bin in loading, and the motor cylin-

der is shielded from the action of the weather which would have a tendency to accelerate the condensation of steam therein. This protection is secured without materially encroaching upon the tank space. At the beginning of its forward stroke the pusher head moves obliquely downward and travels in a curved path over the upwardly curved rear end of the floor plate, carrying forward the lower stratum of the fuel, the major portion of the mass being supported by the slope sheet 18.

While I have shown a desirable and preferred form of construction, various changes in detail may be made without departing from the scope of the invention.

I claim as my invention—

1. In a locomotive tender, in combination, a fuel bin having a floor, a slope sheet at the back of the bin and terminating above the floor, a fuel pusher reciprocable over the floor, a motor back of the slope sheet, and connection between the motor and pusher.

2. In a locomotive tender, in combination, a fuel bin having a floor, a slope sheet at the back of the bin, a fuel pusher reciprocable over the floor, a motor back of and covered by the slope sheet and axially parallel therewith, and connection between the motor and pusher.

3. In a locomotive tender, in combination, a fuel bin having a floor, a slope sheet at the back of the bin, a fuel pusher reciprocable over the floor, a motor back of the slope sheet and axially parallel therewith, connection between the motor and pusher, means for controlling the motor, and adapted to normally stop the motor at the completion of its advance stroke.

4. In a locomotive tender, in combination, a fuel bin having a floor, a slope sheet at the back of the bin, a fuel pusher reciprocable over the floor, a motor back of the slope sheet and axially parallel therewith, connection between the motor and pusher, means for controlling the motor and comprising a valve movable under the influence of the motive fluid for causing the advance stroke of the motor.

5. In a locomotive tender, in combination, a fuel bin having a floor, a slope sheet at the back of the bin, a fuel pusher reciprocable over the floor, a motor back of the slope sheet and axially parallel therewith, connection between the motor and pusher, means for controlling the motor and comprising a manually controlled tubular valve reciprocable therein, a hollow laterally ported valve stem reciprocable in the fluid service pipe and opening through the valve.

6. In a locomotive tender having a fuel bin and a water tank, and, in combination therewith, a fuel pusher reciprocable in the bin, a motor for actuating the pusher, a

valve for controlling the motor and having an exhaust port discharging into the water tank.

7. In a locomotive tender, in combination, 5 a reciprocable fuel pusher, a steam motor for driving the pusher and having the forward end of its cylinder lower than its rearward end, a valve for controlling the steam supply to the motor and adapted to normally maintain pressure in the rearward 10 end of the cylinder, the motor being provided with a drain passage for the discharge of water of condensation.

8. In a locomotive tender having a fuel bin and a water tank and, in combination therewith, a slope sheet separating the rear end of the floor of the bin from the tank and terminating above the floor, a chamber at the back of the slope sheet and open at its 20 lower end, walls closing the space between the bottom of the slope sheet and the floor at each side of the chamber, a fuel pusher reciprocable over the floor of the bin, a motor back of the slope sheet, and connection 25 between the motor and pusher through the chamber.

9. In a locomotive tender, in combination, 30 a fuel bin having a floor, the rearward end of which is upwardly curved, a slope sheet at the back of the bin and terminating above the floor, a fuel pusher reciprocating over

the curved portion of the floor, a motor back of the slope sheet, and connection between the motor and pusher.

10. In combination, a fuel bin having a 35 flat bottom and an inclined rear wall, the meeting portions of these parts being curved, a motor element movable parallel with the rear wall, a wedge-shaped pusher head having a range of movement extending over 40 and beyond the curved portions of the floor and wall in both directions, a link connecting the motor element with the head, and guide flanges under which the head travels.

11. The combination with a locomotive 45 tender having a fuel bin, of a reciprocal fuel pusher for moving the fuel to the forward end of the bin, a motor for actuating the pusher and means for controlling the motor, such means being arranged to stop 50 the motor at the end of each advance stroke of the pusher.

12. The combination with a locomotive tender having a fuel bin and a reciprocal pusher for advancing fuel into the bin, of a 55 fluid motor for actuating the pusher and a valve for controlling the motor, such valve being arranged to automatically stop the motor at the end of each advance stroke of the pusher.

EDWARD RYAN.
